INVENTOR

Caesar R. Bannihr

UNITED STATES PATENT OFFICE.

CAESAR R. BANNIHR, OF WEST CHESHIRE, CONNECTICUT.

BUTTON ORNAMENTING AND ENGRAVING MACHINE.

SPECIFICATION forming part of Letters Patent No. 357,264, dated February 8, 1887.

Application filed November 29, 1886. Serial No. 220,123. (No model.)

To all whom it may concern:

Be it known that I, CAESAR R. BANNIHR, a citizen of the United States, residing at West Cheshire, in the county of New Haven and State 5 of Connecticut, have invented a new and useful Machine for the Purpose of Engraving and Carving Buttons, of which the following is a specification.

My invention relates to improvements in 10 button ornamenting and carving machines, where, by means of milling cutters or drills, the surface of a button may be engraved or carved; and the objects of my improvements are, first, to provide a universal means of indexing, which will present any desired part of 15 the surface of such articles as buttons, knobs, checkers, &c., whether of ivory, pearl, wood, metal, or glass, as well as of the various compositions, to a special milling cutter, drill, or 20 grinder; and, second, to afford facilities for bringing such cutters as named above to bear on the desired parts of the article to be ornamented. I attain these objects by the mechanism illustrated in the accompanying drawings, in which—

Figure 1 is a side view of the complete machine, with the index-arm in perspective; Fig. 2, a front view of the same; Fig. 3, a top view of that part comprising the indexing device, 30 with the positions of the spindles shown by dotted lines. Fig. 4 shows the under side of the same. Fig. 5 shows the top of the arm that holds the spindles which carry the milling-cutters, &c. Fig. 6 shows a top and sectional view of the rotary cylindrical index and chuck. Fig. 7 gives the side view of three milling-cutters and the top view of a button cut with them. Fig. 8 is a sectional view, on an enlarged scale, of the cylindrical index, 35 showing the manner of indexing. Fig. 9 presents a top view, on an enlarged scale, of the index-arm, with universal indexing device containing a chuck holding a button. Fig. 10 is a side view of the same, showing the positions 40 of the horizontal revolving index in relation to the vertical circular index.

Similar letters refer to similar parts throughout the several views.

The base B, shaft A, and spindle-arm C constitute the frame of the machine. The spindle-arm C is secured to the shaft A by a set-

screw drawing together the split hub U. The table of index-arm D turns on the shaft A, and is held in position by the collars L and M, the collar L having a flange, on the edge of which 55 are notches for the pawl K to fall into in changing the arm D from one spindle to another. On the under side of the flange is an annular groove, S, on an eccentric, for the purpose of moving the lever O by means of a roller-pin 60 in the groove S, connected with the slide P. To the lever O is connected the sleeve N, which has at the other end the spring h, which by this mechanism will be moved up or down as the arm D is moved right or left, so that it 65 may engage with a different spindle and index at the same time. On the other or outer end of the index-arm D is the device for holding the article to be worked upon, as in the drawings it is a ball-button, d, which is held 70 by the chuck c. This chuck is placed in the cylindrical index F, which has a bearing in the box E, which has on the side toward the index-arm D the circular index G, and in the center of this is the shaft on which it turns, 75 the shaft passing through the index-arm D and is held in place by the nut and washer on the end.

The index G consists of a hardened-steel ring with notches on its periphery, into which 80 the pawl H catches, which is held down by the spring I, the steel ring having notches of different divisions on its edge, and may be changed so as to have the notches come under the pawl by changing the set-screw l into different holes 85 in the hub, between the box E and arm D; and if more divisions are needed than one ring will admit of it is so arranged that the ring can be taken off and replaced by one with the required divisions. In this way any number 90 of divisions may be had in the index. The pawl H has a V-shaped projection, which drops into the division-notches in the ring G. The manner of indexing with this device is to pull on the handle e outward and upward, and 95 the pawl will be raised by the action of the two inclines of the projection on the pawl and the notch in the ring. The ring will then pass on to the next notch by being moved in the same direction as the handle e, carrying with it all the other parts in the box E; and when 100 all the notches required for the work to be in-

dexed have been used the handle *e* is pushed back into its former or perpendicular position, when the pawl *H* will fall into the starting or first notch and will hold it there by the pressure of the spring *I*, as it will in all the notches as they are used.

The horizontal index consists of the cylinder *F*, having on its circumference and bottom the desired divisions, which are either grooves of 10 the same form as those on the index-ring *G* or as in the drawings, where the divisions are represented by indentations or drill-holes *k*, as shown in Fig. 8. The pins *j*, of which there are as many as there are rows of divisions on 15 the index-cylinder, and which have a conical end which enters the holes *k* as they are brought under the pins when the cylinder is rotated or moved from hole to hole, which is done by turning the handle *e* between the fore- 20 finger and thumb of the operator's left hand. The pins *j* are forced against the cylinder *F* by the action of the spring *h* as it is brought to bear on these ends, as is shown in Fig. 8, either as the arm *D* is moved from spindle to 25 spindle, as hereinbefore described, or as the index *G*, in connection with the box *E*, is turned upon its axis, as shown by the dotted lines in Fig. 10, and as the holes in the cylinder come under the pins the spring *h* will 30 shove them in and will also hold the cylinder *F*, containing the work, from turning while the cutting of the article is being done, and when done the cylinder *F* is turned to the next hole, and in doing so, by means of the two inclines 35 of the drill-hole in the cylinder and the conical end of the pin, the pin is forced out, and as the cylinder turns by the action of the operator's hand, as before said, the pin being forced against it will enter the next hole, as already 40 stated.

The means provided for keeping the pins which are not in use in position and from entering the holes is the spring *i*, having a slot in the end to receive the pins by the groove. 45 (See Fig. 8.) Between each two pins this spring has a split, so that each pin in reality has a spring of its own, which is only strong enough to keep the pin on which it acts in position, and will yield to the action of the spring

50 *h* as it is brought to bear upon it by its movement up or down or by the rotary movement of the box *E*, and by the inclined or curved shape on the inside it will slide upon or pass over them. (See Fig. 8.)

55 The spring *h'*, in connection with the pins on the under side of the box *E*, works in a similar manner by the action imparted to the pitman *Q* by the lever *O*. When the index *G* is used, the pitman *Q* is disconnected.

60 The method shown in the drawings for holding work is mainly for buttons, and consists of the chuck *c*, having a slot through its central part, through which passes the hook, which hooks into the eye of a button and draws it

65 into the chuck by the action of the spiral spring *g* on the other end of the hook-rod which passes through the stem *F'*. (See Fig.

6.) The button *f* is for the spring *g* to act against and to push up on when taking the work from the chuck.

The spindles *a a' a''* are to carry the milling cutters, drills, or grinders, as the case may be, or act as a slide by which a horizontal spindle, *b*, with tool, is brought to act on the work in a similar manner as the other two, *b'' b'''*, are by pressing on the button on top of the spindle with the fingers of the right hand, while the left hand manipulates the indexing by the handle *e*. The spindles are brought up by the action of the spring between the 80 top bearing and the button or knob on its top end, which is loose and held in place with a screw.

The belt which is to impart motion to the spindles carries the pulleys, which are splined. 85 The spline works in a groove in the spindle.

The horizontal spindle *b*, with cutter, may be used in any of the spindles by setting the same by means of the pin *m*, which passes through the casting and into a hole in the 90 pulley, thus keeping it from turning. The pulley on the end of the horizontal spindle *b* is driven by a belt similar to the others, and when the cutter connected therewith is to be used it is brought to the work, as before described. 95

Having described the mechanism and facilities of this machine, it will be seen that by supplying different milling cutters or grinders almost an endless variety of designs may 100 be wrought in as many kinds of material as are used in the arts to which this mechanism is applicable.

I am aware that such parts of this machine as the arm *C*, with the gang of spindles for 105 drilling or milling, is not new, nor is the combination therewith of a swinging table on a column. I therefore do not claim such a combination, broadly; but

What I do claim as my invention, and desire 110 to secure by Letters Patent, is—

1. The combination of the table *D*, with the indexing device around the column or shaft *A*, for the purpose of bringing the table in any desired relation with any of the spindles 115 *a a' a''*, as herein shown and described.

2. The combination of the table or arm *D*, having an indexing device around the shaft *A*, the box *E*, having within it the index *F*, for the purpose of bringing any desired surface of the article in the chuck *c* under the spindles *a a' a''*, as and for the purpose herein shown and described.

3. The combination of the table or arm *D*, having an indexing device around the shaft 125 *A*, box *E*, having within it a horizontal rotary index, *F*, and the vertical circular index *G*, as herein shown and described, and for the purpose specified.

4. The combination of the table or arm *D*, 130 having an indexing device around the shaft *A*, and box *E*, having within it the index *F* in a horizontal relation to the vertical index *G* in relation to the spindles *a a' a''*, with cut-

ters or grinders $b' b'' b'''$, for the purpose of cutting or grinding designs upon articles, as herein fully shown and described.

5. The combination, in an indexing device, of the pins j , springs i and h , box E , and cylinder F , provided with holes k , substantially as and for the purpose set forth.

6. The combination of the cam or eccentric groove S , with a slide, P , lever O , sleeve N , and spring h , pitman Q , and spring h' , for the purpose of changing the index while the arm D is moved from one spindle to an-

other, all for the purpose herein set forth and described.

7. The combination of a horizontal spindle, b , with a vertical spindle, a , in which the vertical spindle forms a plunger or slide for the horizontal spindle, being set by means of the pin m , as herein set forth and described.

CAESAR R. BANNIHR.
